[57] CLAIM

The ornamental design for a cable modem housing, as shown and described.

DESCRIPTION

FIG. 1 is a front, top and right perspective view of one embodiment of the cable modem housing;

FIG. 2 is a left side elevational view of the cable modem housing shown in FIG. 1;

FIG. 3 is a top plan view of the cable modem housing shown in FIG. 1;

FIG. 4 is a front elevational view of the cable modem housing shown in FIG. 1;

FIG. 5 is a bottom plan view of the cable modem housing shown in FIG. 1;

FIG. 6 is a right side elevational view of the cable modem housing shown in FIG. 1;

FIG. 7 is a rear elevational view of the cable modem housing shown in FIG. 1;

FIG. 8 is a front, top and right isometric view of another embodiment of the cable modem housing;

FIG. 9 is a left side elevational view of the cable modem housing shown in FIG. 8;

FIG. 10 is a top plan view of the cable modem housing shown in FIG. 8;

FIG. 11 is a front elevational view of the cable modem housing shown in FIG. 8;

FIG. 12 is a bottom plan view of the cable modem housing shown in FIG. 8;

FIG. 13 is a right side elevational view of the cable modem housing shown in FIG. 8; and,

FIG. 14 is a rear elevational view of the cable modem housing shown in FIG. 8.

The broken line showings in FIGS. 1-7 are for illustrative purposes only and form no part of the claimed first embodiment.
